[57] CLAIM

The ornamental design for a gazebo, as shown.

DESCRIPTION

FIG. 1 is an upper right front perspective view of a gazebo, showing my new design.

FIG. 2 is a top view thereof with the finial removed.

FIG. 3 is a front view of an entry panel of the gazebo thereof.

FIG. 4 is a front view of a side panel thereof.

FIG. 5 is an enlarged fragmentary view thereof, taken from circle 5 of FIG. 4.

FIG. 6 is a front right perspective view of a roof panel thereof.

FIG. 7 is an enlarged front view taken from circle 7 of FIG. 6 thereof.

FIG. 8 is a top view of an enlarged portion of a side panel thereof taken from circle 8 of FIG. 1.

FIG. 9 is a bottom rear left perspective view of the gazebo thereof.
